ABSTRACT OF THE DISCLOSURE

Compounds of the formula

wherein

R_1 is hydrogen; alkyl of 1 to 17 carbon atoms; mono-, di- or tri-halo-substituted alkyl of 1 to 17 carbon atoms; alkenyl of 2 to 17 carbon atoms; alkoxy of 1 to 2 carbon atoms; phenyl; 2,4-dichlorophenoxy-methyl; or α -(2,4-dichlorophenoxy)-ethyl; and

R_2 is disubstituted acyclic amino or optionally substituted monocyclic or bicyclic heterocyclic amino;

the compounds are useful as contact or systemic biocidal or biostatic agents, especially against mildew and various other fungi.

This invention relates to novel 1,1,1-trichloro-2-amido-2-amino-ethanes, as well as to methods of preparing these compounds.

More particularly, the present invention relates to compounds of the formula

wherein

R_1 is hydrogen; alkyl of 1 to 17 carbon atoms; mono-, di- or tri-halo-substituted alkyl of 1 to 17 carbon atoms; alkenyl of 2 to 17 carbon atoms; alkoxy of 1 to 2 carbon atoms; phenyl; 2,4-dichlorophenoxy-methyl; or α -(2,4-dichlorophenoxy)-ethyl; and

R_2 is

where

R_3 is allyl, cyclohexyl, 2-propinyl, 1-methyl-2-propinyl or 2-cyano-ethyl, and

R_4 is alkyl of 1 to 4 carbon atoms, allyl or 2-cyano-ethyl;

where R_5 is

where

R_7 is hydrogen, halogen, thiocyanato, alkyl of 1 to 4 carbon atoms, alkoxy of 1 to 4 carbon atoms,

2

alkylthio of 1 to 4 carbon atoms, alkylsulfoxide of 1 to 4 carbon atoms, alkylsulfonyl of 1 to 4 carbon atoms or COOR_{10} , where R_{10} is hydrogen or alkyl of 1 to 4 carbon atoms;

R_8 is hydrogen, halogen, alkyl of 1 to 4 carbon atoms or alkoxy of 1 to 4 carbon atoms; and

R_9 is hydrogen, halogen or alkyl of 1 to 4 carbon atoms,

and R_6 is alkyl of 1 to 4 carbon atoms, hydroxy-alkyl of 1 to 4 carbon atoms, cyano-alkyl of 1 to 4 carbon atoms, allyl, 2-propinyl, benzyl or cyano;

15 where n is 2, 4 or 6;

20

25

30 where

35 R_{12} is hydrogen, alkyl of 1 to 3 carbon atoms, nitro, benzyl, phenyl or halogen; and

R_{13} is hydrogen, alkyl of 1 to 3 carbon atoms or phenyl;

40 (h)

45

50 where R_{14} , R_{15} and R_{16} , which may be identical to or different from each other, are each hydrogen or alkyl of 1 to 3 carbon atoms;

55 where R_{17} is hydrogen or alkyl of 1 to 17 carbon atoms;

60

65

70

where R_{18} is hydrogen, methyl, phenyl, monochlorophenyl, pentachloro-phenyl, nitroso, cyano, β -hydroxy-ethyl,

3

where

R₁₉ is hydrogen or one equivalent of sodium, potassium, ammonium, zinc, copper (II) or manganese (II) cation; 10

R₂₀ is hydrogen; alkyl of 1 to 10 carbon atoms; mono-, di- or tri-halo-substituted alkyl of 1 to 10 carbon atoms; alkenyl of 2 to 3 carbon atoms; phenyl; or 2,4-dichlorophenoxy-methyl; 15

R₂₁ is hydrogen; alkyl of 1 to 12 carbon atoms; mono-, di- or tri-halo-substituted alkyl of 1 to 12 carbon atoms; methoxy-alkyl of 1 to 12 carbon atoms; or cyclohexyl; alkyl; phenyl; or 20

R₂₂ is hydrogen; phenyl; monohalo-phenyl, dihalo-phenyl, allyl, alkyl of 1 to 4 carbon atoms, or benzyl; 25

R₂₃ is hydrogen, methyl or ethyl; 30

R₂₄ and R₂₅ are methyl or ethyl, and n is 2 or 3; 35

(m)

or

(n)

The compounds embraced by Formula I above may be prepared by various methods involving well known chemical principles, among which the following are particularly preferred. 45

By reacting a 1,1,1-trichloro-2-amido-ethane of the formula 50

wherein R₁ has the same meanings as in Formula I and R₂₈ is a substituent which can be readily split off as an anion, preferably bromine or chlorine, with a secondary amine of the formula 55

wherein R₂ has the same meanings as in Formula I. The reaction is advantageously performed in the presence of an acid acceptor, preferably a tertiary aliphatic amine, such as triethylamine. If the amine of the Formula III is a relatively strong base, a commensurate excess over the stoichiometric amount required for reaction with compound II may serve as the acid acceptor. The reaction is advantageously also performed in the presence of an inert organic solvent, such as acetone, ether, tetrahydrofuran, methylene chloride, dimethylformamide or a lower alkanol. 65

A compound of the Formula I wherein R₂ is a piperazine substituent of the formula shown under (1) above, may also be prepared by reacting a piperazine of the formula 70

3,707,477

4

(IV)

wherein R₁₈ has the same meanings as in Formula I, with a 1,1,1-trichloro-2-amido-ethane of the Formula II as previously described, or also by converting a 1,1,1-trichloro-2-amido-2-piperazino-ethane of the formula

(V)

wherein R₁ has the same meanings as in Formula I, into a 1,1,1-trichloro-2-amido-2-(N'-substituted piperazino)-ethane of the formula

(VI)

by reaction with the desired reaction partner, such as 20 HNO₂, acylating agent, isocyanate, etc.

The starting compounds of the Formula V or their salts may be prepared by reacting a 1,1,1-trichloro-2-amido-ethane of the Formula II with piperazine within a very definite pH-range. If the reaction is carried out at a pH above the optimum value, symmetrical di-substitution products of the formula

are formed. On the other hand, at a pH below the optimum value no reaction at all takes place. Thus, the compounds of the Formula V and their salts may be used as starting materials for a variety of asymmetrically substituted piperazine derivatives and are therefore useful as intermediates for the preparation of biocidal and biostatic agents. 35

Compounds of the Formula I wherein R₂ is a morpholino substituent of the formula shown under (e) may 40 be prepared by reacting a morpholine of the formula

(VII)

wherein R₁₁ has the same meanings as in Formula I, with a compound of the Formula II in the presence of an acid acceptor; or also by reacting a bis-(β-chloro-ethyl)-ether of the formula

(VIII)

wherein R₁₁ has the same meanings as in Formula I, with a 1,1,1-trichloro-2-amido-2-amino-ethane of the formula

(IX)

wherein R₁ has the same meanings as in Formula I.

The following examples further illustrate the present invention and will enable others skilled in the art to understand it more completely. It should be understood, however, that the invention is not limited solely to the particular examples given below.

EXAMPLE 1

A solution of 2.5 gm. of N-(1,2,2,2-tetrachloroethyl)-methacrylamide in tetrahydrofuran was added dropwise to a mixture of 1.13 gm. of N-methyl-cyclohexylamine, 1.2 gm. of triethylamine and 25 ml. of tetrahydrofuran,

5

accompanied by stirring. Thereafter, the reaction mixture was stirred for one hour at room temperature, and then the precipitated triethylamine hydrochloride was separated by vacuum filtration, the filtrate was evaporated in vacuo, and the liquid residue was dissolved in hexane. The resulting solution was treated with activated charcoal, filtered and evaporated in vacuo. The oily, slightly yellow product was dried at 50° C. and 0.5 mm. Hg, yielding the compound of the formula

Analysis Calculated (percent): C, 47.7; H 6.5; N, 8.6. *Found* (percent): C, 47.5; H, 6.5; N, 8.3.

EXAMPLE 2

A solution of 6.7 gm. of N-(1,2,2,2-tetrachloroethyl)-pivalic acid amide in tetrahydrofuran was added dropwise at room temperature to a solution of 3 gm. of N-phenylcyanamide in 50 ml. of tetrahydrofuran, and then 3 gm. of triethylamine were added while stirring. The resulting mixture was stirred for one hour at room temperature, the precipitated triethylamine hydrochloride was separated by vacuum filtration, the filtrate was evaporated in vacuo, and the semi-solid residue extracted three times with warm hexane. The residual colorless, crystalline substance, M.P. 121–124° C., was identified to be the compound of the formula

EXAMPLE 3

A solution of 8.4 gm. of N-(1,2,2,2-tetrachloroethyl)-formamide in 40 ml. of tetrahydrofuran was added dropwise to a solution of 7.44 gm. of N-methyl-4-bromo-aniline and 4.2 gm. of triethylamine in 60 ml. of tetrahydrofuran, while stirring. The resulting mixture was stirred for two hours at room temperature, and then the precipitated triethylamine hydrochloride was separated by vacuum filtration, the filtrate was evaporated in vacuo, and the residue was crystallized by digestion with hexane. The crystalline raw product was recrystallized from methanol, yielding the compound, M.P. 130–131° C., of the formula

EXAMPLE 4

A solution of 5 gm. of N-propargyl-3,4-dichloroaniline and 2.6 gm. of triethylamine in 30 ml. of tetrahydrofuran was added dropwise at room temperature to a solution of 7.2 gm. of N-(1,2,2,2-tetrachloroethyl)-benzamide in 50 ml. of tetrahydrofuran, accompanied by stirring. The resulting mixture was stirred at room temperature for one hour more, the tetrahydrofuran was then distilled off in vacuo, and the solid residue was recrystallized from benzene, yielding the colorless crystalline compound, M.P. 122–124° C., of the formula

EXAMPLE 5

(a) A solution of 10.5 gm. of N-(1,2,2,2-tetrachloroethyl)-formamide in 30 ml. of ethylacetate was added dropwise to a mixture of 3.4 gm. of imidazole, 5 gm. of triethylamine and 50 ml. of ethylacetate, accompanied by stirring. The resulting mixture was stirred for two hours

6

at room temperature, and then the precipitated triethylamine hydrochloride was filtered off, and the filtrate was evaporated in vacuo. The oily residue was caused to crystallize by treatment with warm benzene, and the crystalline raw product was recrystallized from benzene, yielding the compound, M.P. 101–103° C., of the formula

(b) A solution of 10.5 gm. of N-(1,2,2,2-tetrachloroethyl)-formamide in 50 ml. of methyl ethyl ketone was added dropwise to a solution of 3.4 gm. of imidazole in 50 ml. of methyl ethyl ketone, whereby a crystalline precipitate was immediately formed which was collected by vacuum filtration, extracted with warm acetonitrile, and dried at 40° C. A finely crystalline, colorless, readily water-soluble substance, M.P. 210° C. (decomp.), was obtained which was identified to be N-[(1-formamido-2,2,2-trichloroethyl)-ethyl]-imidazole hydrochloride.

EXAMPLE 6

25 A solution of 6.5 gm. of N-(1,2,2,2-tetrachloroethyl)-chlorocetamide in 25 ml. of tetrahydrofuran was added dropwise at room temperature to a mixture of 3 gm. of benzotriazole, 2.6 gm. of triethylamine and 25 ml. of tetrahydrofuran, accompanied by stirring. The resulting 30 mixture was stirred for two hours at room temperature, and then the precipitated triethylamine hydrochloride was separated by vacuum filtration and the filtrate was evaporated in vacuo. The liquid residue crystallized throughout upon standing, and was then recrystallized from isopropanol, yielding the compound, M.P. 195–197° C., of the 35 formula

EXAMPLE 7

40 45 A solution of 34.4 gm. of piperazine in 220 ml. of water was adjusted to a pH of 4.0 by addition of 2 N hydrochloric acid (about 500 ml. of HCl were required). While vigorously stirring the acidic solution, a solution of 84 gm. of N-(1,2,2,2-tetrachloroethyl)-formamide in 200 ml. of acetone and an aqueous concentrated solution of 80 gm. of sodium acetate were simultaneously added; the rate of addition of the sodium acetate solution was metered in such a way that the pH of the mixture remained at 4.0±0.1. Thereafter, the mixture was stirred for fifteen minutes more at room temperature, then the small amount of precipitated N,N-bis-(1-formamido-2,2,2-trichloroethyl)-piperazine was filtered off, and the filtrate was admixed with 200 ml. of aqueous 20% sodium hydroxide while cooling to 50° C. Subsequently, 200 ml. of methylene chloride were added, and the aqueous phase was separated and saturated with potassium carbonate. A colorless, crystalline precipitate was formed which was collected by vacuum filtration and recrystallized from acetone, yielding the water-soluble free base, M.P. 122–123° C., of the formula

70

The hydrochloride, M.P. 182° C. (decomp.), was obtained by adding the calculated amount of hydrochloric acid to an aqueous solution of the free base, and gently evaporating the mixture in vacuo.

7
EXAMPLE 8

5.6 gm. of powdered N-(o-chloro-phenyl)-piperazine monohydrochloride monohydrate were suspended in a mixture of 50 ml. of tetrahydrofuran and 5.1 gm. of triethylamine, and then, while stirring, a solution of 5.3 gm. of N-(1,2,2,2-tetrachloro-ethyl)-formamide was added dropwise at room temperature. The resulting mixture was stirred at room temperature for two hours more and then for one hour at 65° C., the precipitated triethylamine hydrochloride was separated by vacuum filtration, the filtrate was evaporated in vacuo, and the residue was made to crystallize by treatment with ethanol. The crystalline raw product was recrystallized from ethanol/water, yielding the compound, M.P. 153–155° C., of the formula

EXAMPLE 9

A solution of 1.4 gm. of potassium cyanide in 15 ml. of water was added dropwise to a vigorously stirred mixture of 3.2 gm. of bromine and 40 ml. of water. After disappearance of the bromine color, 5.2 gm. of N-(1-formamido-2,2,2-trichloro-ethyl)-piperazine were added in several small portions to the bromocyan solution. Thereafter, 2.06 gm. of sodium carbonate were added, and the mixture was stirred for two hours at room temperature. The precipitate formed thereby was collected by vacuum filtration, dried at room temperature and dissolved in chloroform, and the solution was admixed dropwise with ether, yielding the colorless crystalline compound, M.P. 109–110° C. of the formula

EXAMPLE 10

While vigorously stirring a solution of 2.6 gm. of N-(1-formamido-2,2,2-trichloro-ethyl)-piperazine in 20 ml. of tetrahydrofuran at 50° C., first a solution of 0.76 gm. of carbon disulfide in 10 ml. of tetrahydrofuran and then 5 ml. of 2 N sodium hydroxide were added dropwise thereto, and the mixture was stirred for one hour at room temperature. Thereafter, the tetrahydrofuran was distilled off in vacuo on a water bath at 40° C., the residue was stirred with isopropyl ether, the mixture was vacuum-filtered, and the filter cake was dried at room temperature, yielding the yellowish crystalline sodium dithiocarbamate of the formula

3.6 gm. of the sodium salt were dissolved in 60 ml. of ethanol and, while stirring the solution, a solution of 0.7 gm. of zinc chloride in 50 ml. of ethanol was added dropwise thereto. The mixture was stirred at room temperature for 30 minutes, and then 150 ml. of water were added. The precipitate formed thereby was collected by vacuum filtration, washed with water and dried at 50° C., yielding the corresponding zinc salt, M.P. 250° (decomp.), of the formula

EXAMPLE 11

A solution of 3.2 gm. of triethylamine in 25 ml. of tetrahydrofuran was added dropwise to a solution of 3.4 gm. of N-formyl-piperazine and 6.3 gm. of N-(1,2,2,2-tetrachloroethyl)-formamide in 75 ml. of tetrahydrofuran, while stirring. The resulting mixture was stirred for

two hours more at room temperature, the precipitated triethylamine hydrochloride was vacuum-filtered off, and the tetrahydrofuran was distilled out of the filtrate in vacuo. The residual raw product was recrystallized from ethanol, yielding the compound, M.P. 98–101° C., of the formula

EXAMPLE 12

1.22 gm. of acetic acid anhydride were added to a solution of 3.9 gm. of N-(1-formamido-2,2,2-trichloro-ethyl)-piperazine in 10 ml. of tetrahydrofuran, and the mixture was heated at its boiling point for two hours. Thereafter, the reaction mixture was allowed to cool, poured over ice, and the precipitated semi-solid product was extracted with five 15 ml.-portions of methylene chloride. The combined extract solutions were dried over sodium sulfate and then evaporated, and the residue was recrystallized from isopropanol/hexane, yielding the compound, M.P. 149–150° C., of the formula

EXAMPLE 13

17.2 gm. of piperazine were dissolved in water, and pH of the resulting solution was adjusted to 2.0 by addition of 2 N hydrochloric acid. While vigorously stirring the acidic solution, 42 gm. of powdered N-(1,2,2,2-tetrachloro-ethyl)-formamide were added in small portions, and simultaneously a concentrated aqueous sodium acetate solution was added at a rate such that the pH was maintained at 2.0±0.1. Thereafter, the acidic reaction solution was carefully saturated with potassium carbonate. The oil precipitated thereby was taken up in ethanol, and the resulting solution was allowed to stand for 12 hours at room temperature. The small amount of precipitated N,N'-bis-(1-formamido - 2,2,2 - trichloro - ethyl)-piperazine was filtered off, the ethanol was distilled out of the filtrate, and the semisolid residue was recrystallized from ethanol/water, yielding the compound, M.P. 77–80° C., of the formula

The product was insoluble in dilute alkalis.

EXAMPLE 14

A solution of 1.6 gm. of tetrahydrofurfuryl chloroformate in 20 ml. of methyl ethyl ketone was added dropwise to a solution of 2.6 gm. of N-(1-formamido-2,2,2-trichloroethyl)-piperazine and 1.1 gm. of triethylamine in 30 ml. of methyl ethyl ketone, while stirring. The resulting mixture was heated at its boiling point for ten minutes, then cooled and poured into ice water. The oil which precipitated out was extracted with benzene, and the extract solution was washed with water, dried with sodium sulfate and evaporated in vacuo. The oily residue crystallized upon stirring with hexane, yielding the compound, M.P. 72–75° C., of the formula

EXAMPLE 15

2.6 gm. of N-(1-formamido-2,2,2-trichloro-ethyl)-piperazine were dissolved in 5 ml. of 2 N hydrochloric acid, the solution was cooled to 5° C., and then a solution of 0.97 gm. of potassium cyanate in 20 ml. of water was

added. The resulting mixture was stirred for 30 minutes at room temperature, whereupon a colorless precipitate began to form. The mixture was allowed to stand for twenty hours at room temperature, and the precipitate was collected by vacuum filtration, washed with water and dried below 50° C., yielding the compound, M.P. 175-176° C., of the formula

EXAMPLE 16

0.71 ml. of methyl isocyanate were added to a solution of 2.6 gm. of N-(1-formamido-2,2,2-trichloroethyl)-piperazine in 10 ml. of absolute tetrahydrofuran, and the

5 resulting mixture was allowed to stand at room temperature for 18 hours. Thereafter, the tetrahydrofuran was distilled off in vacuo, and the solid residue was recrystallized from isopropanol/hexane, yielding the compound, M.P. 166-167° C. (decomp.), of the formula

10

Using procedures analogous to those described in Examples 1-16 and correspondingly substituted starting compounds, the compounds listed in the following tables 15 were also prepared:

an effective contact and systemic fungicide for use on plants infested with genuine mildew and similar fungi.

(b) The same results were obtained with a wettable powder compounded in like manner from the following ingredients:

	Parts
1,1,1 - trichloro - 2 - formamido - 2 - (N'-ethoxycarbonylpiperazinoethane	80
Calcium lignin sulfonate	8
Colloidal silicic acid	5
Sodium sulfate	5
Diisobutyl-naphthalene sodium sulfonate	2

EXAMPLE 193

Aerosol spray

The aerosol composition was compounded from the following ingredients:

	Parts
1,1,1 - trichloro - 2 - formamido - 2 - (N' - formyl - piperazino) - ethane	0.05
Sesame oil	0.10
N - Methyl - pyrrolidone	10.00
Mixture of Frigen 11 and 12	89.85

The trichloroethane compound, the sesame oil and the N-methyl-pyrrolidone were admixed with each other, and the mixture was charged into an aerosol can equipped with an aerosol spray valve. The cans were then pressurized with the propellant gas mixture in conventional manner. The aerosol spray discharged from the pressurized can was an effective fungistatic contact composition for use in inhibiting the growth of *Aspergillus niger*.

While the present invention has been illustrated with the aid of certain specific embodiments thereof, it will be readily apparent to others skilled in the art that the invention is not limited to these particular embodiments, and that various changes and modifications may be made without departing from the spirit of the invention or the scope of the appended claims.

We claim:

1. A compound of the formula

wherein

R₁ is hydrogen; lower alkyl; or mono- or di-halo-substituted lower alkyl;

R₁₂ is hydrogen; alkyl of 1 to 3 carbon atoms; nitro; or phenyl; and

R₁₃ is hydrogen; alkyl of 1 to 3 carbon atoms; or phenyl.

2. The compound of the formula
